UNITED STATES PATENT OFFICE

2,609,167

TAILLESS CONVERTIBLE AIRPLANE AND
ROADMOBILE

Adelard J. Gero, Jr., Taftville, Conn.

Application November 30, 1948, Serial No. 62,625

3 Claims. (Cl. 244—49)

1

This invention relates to a tailless convertible airplane and roadmobile.

An object of this invention is the construction of an efficient tailless convertible airplane and roadmobile apparatus.

Another object of this invention is to incorporate in one apparatus a new airplane stabilizing and controlling means; winglift increasing device; three position single action control system with operating mechanism; a wing folding system for roadmobile conversion with operating mechanism; roadmobile propulsion means; propeller safety means; simplified torque type landing gear; and simplified overall structure.

A still further object is the production of an apparatus that increases the personal plane utility, inherent safety, control simplicity, low cost and a practical compact apparatus to serve its owner from his home garage, like the automobile, without removal of wings, tail structure and propeller.

This invention eliminates present tailless flight methods such as reflex or stable airfoils, low lift coefficients, large sweepback unfavorable and critical position of C. G. needed, high take-off and landing speed, wing tip stalling where controllers are located making them non-effective and large spans and wing area required.

These disadvantages are eliminated by the addition of this stabilelevator below the lower aft trailing edge surface of any aircraft main lifting wing, effective on any airfoil section, or any wing plan form, and mounted to pivot to any negative angle and effective with any airfoil section. This stabilelevator will be deflected by the constant lower wing surface high pressure airflow and the wing trailing edge downwash airflow causing a powerful and efficient stabilizing and controlling device. This stabilelevator as shown does not disrupt the airflow over the wing surfaces preventing a loss of wing lift when operated. When this aircraft is unbalanced by a rising or falling airflow disturbance, this device will be deflected by this airflow at a negative or positive angle, causing a corrective positive or negative pitching moment or lifting load at trailing edge with resultant inherent stability, non-stalling and non-spinnable characteristics. This aircraft control system and stabilelevator eliminates the necessity of "control feel" and results in decreased flight-learning time and expense.

It eliminates the section instability felt on most high camber airfoil section at all angles of attack with the longitudinal stability remaining positive at all non-stalled negative angles of

2

stabilelevator, making any airfoil section inherently stable without the necessity of restoring the normal flying altitudes after a disturbance by a manipulation of controls and reducing piloting skill to a minimum.

The stabilelevator action alone maneuvers this aircraft along all flight axis with inherent safety and velocity limitation. This aircraft is controlled to high angles to take advantage of conventional leading edge slots and with complete wing acting as one large landing flap, resulting in high lift and drag for slow speed flight.

When pivoted, the stabilelevator movements are aft, changing angles and varying the pitching moments for stabilizing and controlling this aircraft.

The stabilelevators should never be permitted to pivot forward to a positive angle, because this will cause a diving moment, or a crash dive if control system fails. This danger is eliminated by adding a horizontal stop 39 fixed to an actuating arm which bears against a vertical stop 38 fixed to a hinge bracket 36. These stops restrict rotation of an actuating arm 35 clockwise from neutral position for anti-positive action.

Also incorporated to wing leading edge are means for increasing the over-all wing efficiency and aircraft performance by adding a conventional slot 24 and located at lower wing surface entrance to a slot 24, an airflow deflector flap or slot-flectors 25 made to open to negative angles (Fig. 12—dotted) by having its rear tube edge 26 pivoted and hinged to bearings 26 which are fixed to wing ribs.

The advantages for this slotflector 25 is that a greater volume of air is deflected through a conventional slot 24 improving the over-all wing efficiency and aircraft performance, such as increasing wing lift coefficients on any airfoil section especially symmetrical sections with its ideal tailless characteristics. It increases positive pitching moments for controlling stalls at low or high angle of attack for quick take-off and slow landings, increasing boundary layer airflow over wing surface at high angles of attack, changing any airfoil lift curve from a sharp lift peak to a rounded lift peak, increasing camber on any airfoil section, forward movement of aero-dynamic center as lift coefficient is increased, decreases wing area required because of higher wing lift obtainable resulting in a compact wing span and machine. Wing tip stalling is eliminated and stallproofing this aircraft is accomplished by having the slotflector made into two sections, the

55 inboard and outboard slotflectors.

The inboard section is adjusted to deflect a smaller volume of air through a slot 24 stalling this inboard panel first and results in lowering nose of aircraft before the outboard wing panel stalls. This action is combined with stabilelevators 37 which have inherent stalling characteristics of their own, to provide the necessary pitching moment to hold the aircraft at a controlled stalled high angle of attack altitude without stalling completely, making this aircraft inherently stable and stallproof, because the stabilelevators and slotfactors will be deflected at positive angles if stalled completely causing a nose lowering moment. This system will eliminate the necessity of installing wing stalling indicator and instruments for 15 warning purpose.

With the foregoing and other objects in view, this invention comprises certain novel constructions, combinations, and arrangements of parts as will be hereinafter fully described, illustrated 20 in the accompanying drawings, and more particularly pointed out in the appended claims.

In the drawings:

Figure 1 is a top plan view of the apparatus, constructed in accordance with this invention, 25 and showing the same in an open position, ready for flying, while

Figure 2 is a view in front elevation of the same.

Figure 3 is a view in side elevation, showing 30 the wings of the apparatus in a folded position, as when the apparatus is used as a motor vehicle, while

Figure 4 is a top plan view of the same.

Figure 5 is a view in front elevation of the apparatus shown in Figures 3 and 4.

Figure 6 is an enlarged, fragmentary view, partly in horizontal section of the apparatus.

Figure 6A is an enlarged, fragmentary view, partly in horizontal section of the apparatus.

Figure 7 is an enlarged, vertical, fragmentary, longitudinal, sectional view of the apparatus, while

Figure 7A is a similar view of the rear portion of the apparatus.

Figure 8 is an enlarged, fragmentary, vertical, transverse, sectional view of the body and one of the wings, on line 8-8 of Figure 7A.

Figure 8A is a vertical, sectional view, taken on line 8A-8A of Figure 7A.

Figure 9 is a sectional view, taken on line 9-9, Fig. 6A, looking in the direction of the arrows.

Figure 10 is a sectional view, taken on line 10-10, Fig. 7, and looking in the direction of the arrows.

Figure 11 is a sectional view, taken on line 11-11, Fig. 6, and looking in the direction of the arrows.

Figure 12 is a sectional view, taken on line 12-12, Fig. 6, and looking in the direction of the arrows.

Referring to the drawings, in which I have illustrated the preferred embodiment of my invention, I designate the body of the apparatus, which body 1 is provided with suitable axles 2 having wheels 3 suitably mounted thereon. The body 1 is provided with large windows 4 for increased visibility and safety.

In the body 1 and at the rear portion thereof is positioned a motor 5. This motor 5 is mounted on suitable brackets 6, and these brackets are secured to portions of the framework 7 within the body 1. A propeller 8 is suitably connected to the motor 5. By means of the motor 5 and 70

propeller 8, the apparatus can be driven over a roadway, when it is being used as a motor vehicle, or when the apparatus is flying, the motor and propeller are the means for driving the ship through the air.

Within the body 1 there is provided a floor 9 (Fig. 7), above which is a steering or control wheel 10; this wheel 10 is fixedly secured to a rod 11 that is suitably mounted on wall 12 of the body 1. The rod 11 is adapted to have a longitudinal movement, as shown by dotted lines, for the purpose of operating rod 20. On rod 11 is mounted a key section 13 (Figs. 7 and 10). The rod 11 extends through an inverted U-shaped bracket 14 that is mounted on the wall 12. An arm 15a of hub 15 extends up under bracket 14. The lower end of arm 15a is connected by a universal joint 16 to the arm 17 that is fixedly secured to the top of steering post 18. The lower end of steering post 18 is suitably connected to steering wheel 19.

The push-and-pull rod 20 is connected at one end (Fig. 7) to the outer end of rod 11. The opposite end of rod 20 extends through tube 21.

A control rod 21a is connected at its upper end to the outwardly extending portion 21b of hub 15; this rod 21a is pivotally connected at its lower end to arm 21c which is fixedly secured to tube 21. Rod 11 is provided with a key-way 11a into which extends the key 15a of hub 15, Fig. 10. On the inner end of rod 20 is block 20a, Fig. 7A. Links 20b are pivotally connected at their lower ends to block 20a, and also pivotally connected at their upper ends to arm 20c. Arm 20c is pivotally connected to bearing 20e, which bearing 20e is secured to tube 21. Rod 41 is pivotally connected at its lower end to cross rod 20f. The upper end is pivotally connected to universal block 41a.

Tube 21 pivots bearing 20e, and also pivots at the same time arm 20c, links 20b and block 20a to the dotted position as shown in Fig. 8. When tube 41 is operated vertically, it actuates said block 41a and segment gear 41b. Gear 41b meshes with gear 41c which is on worm gear 47 (Fig. 8). Through this structure the control tube 45 is operated.

Attached by a hinged connection 22, at each side of the body 1, is a wing 23 (Fig. 4). Each wing 23 is of a hollow structure, with a fixed wing slot 24 near its forward end (Fig. 12). This wing slot 24 is for the air flow to pass through and over the wing, and to control this airflow, a deflector 25 is hingedly mounted at 26 (Fig. 12). This deflector 25 is provided with an upstanding bracket 27, to which is pivotally connected operating rod 28; the inner end of rod 28 is pivotally connected to the lower bell-crank 29a, pivotally mounted on bracket 30 (Fig. 11). Each of the several deflectors 25 has its operating rod 28 connected to one end of the lower bell-crank 29a. It is to be understood that there are four of these deflectors, two being on each wing 23. The movement of the tube 45 operates the upper bell-crank 29, and also operates through sectional keyed hub 29b bell-crank 29a. Bell-crank 29 is movably connected to rod 33. Rod 33 is attached at its outer end, at 34, to the inner or upper end of lever 35. Lever 35 is pivotally mounted on the outer end of bracket 36. A stabilizer 37 is fixedly secured to the outer or lower end of lever 35 and can be adjusted to the different dotted positions, for the purpose hereinafter described. A stop bracket 38 is fixedly secured to the rear portion

of the wing 23, and the lever 35 is provided with an outstanding lug 39, which engages the bracket 38 for preventing the stabilizer moving too far downward and forward. A second bracket 36a (Fig. 6) is attached to the framework of the wing 23, and a lever arm 35a is mounted on said bracket and is attached to said stabilizer 37, in the mounting of the stabilizer on the wing 23.

Referring to Figures 7A, 8 and 8A, the vertical rods 40 are provided with pivoted bars 42 at their lower ends. Each bar 42 is provided with an elongated S-shaped slot 43. Each rod 40 is provided with a pivoted yoke 44 at its upper end. An arm 40a is fixedly secured to 21. Arm 40a is provided with an integral cam pin 40b, which cam pin extends through S-shaped slots 43. When tube 21 is rotated cam pin 40b actuates 43, as before mentioned.

Bars 42 are pivotally supported at 42a on the framework.

When rod 40 is operated vertically, it rotates control tube 45, and pivots finger cam 45a (Figs. 6 and 12), which pushes down on lower bell-crank 29a, and disengages 29a from upper bell-crank 29, to stop operation of the deflectors 25.

A coil spring 29c is provided for normally holding the lower bell-crank 29a in meshing engagement with the upper bell-crank 29.

When lower bell-crank 29a is disengaged, key 29d will enter the key-way 29e, thereby locking deflector 25 in its closed position.

Each wing 23 is provided with a universal hinge section 22 (Fig. 6A). This section is provided with a threaded extension 22a in the block 22b. The wing is provided with a fixed tongue 22c, which is positioned in said hinge section 22. A bolt 22d extends through the tongue 22c and hinge section, holding same together. A fixed tongue 22e extends into bracket 22f, which bracket 22f is secured to the body 1. A threaded pin 22g is on bracket 22f and extends through the tongue 22e (Fig. 9). To release tongue 22e a crank 22x is employed to rotate threaded pin 22g so that it will release tongue 22e. On the upper end of thread pin 22g is a safety lever 22h, which is mounted on pin 22g by an integral web 22i. Safety lever 22h has a cam slot 22j. A bolt 22k has pin 22l extending through cam slot 22j. Brackets 22m are secured to body 1. A tongue 22h is fastened to the wing 23. When positioned as shown in Fig. 9, the bolt 22k locks the wing in an open position. It is also to be understood that when threaded pin 22g releases tongue 22e it also releases 22h by the means hereinbefore described and as clearly shown in dotted line, Fig. 9.

From the horizontal flying position, the wings are free to rotate on universal hinge sections 22 to a vertical position as shown by dotted lines 22° (Fig. 6A), then they are folded against the body, as shown at 22p. A lug 22q extends from the upper edge of the wing and is adapted to extend into bracket 22m, being held in this position by bolt 22k, hereinbefore mentioned.

Main control tube 45 is composed of sections 45a. These sections 45a are connected by interlocking joints 45b. When the wings are rotated and folded against the body 1, the sections are separated at the interlocking joints 45b.

When the wings are in their folded position (22p, Fig. 6A), the stabilizer is free to pivot to the position shown by dotted line 37 (Fig. 12) and held in this position by a lock 37a (Fig. 6A) engaging section tube 45a.

Referring particularly to Figs. 2 and 4: a connecting bar 49 is composed of two hinged sections. The bar 49 is mounted on brackets 50; brackets 50 are on the wing tips. 5 Screws 51 are extended through the bar 49 and into brackets 50, thereby detachably supporting bar 49 on the wing tips. A pair of brackets 52 is mounted on the sectional bar 49, and each bracket 52 is provided with a skid wheel 53. 10 This device constitutes a bumper, as well as a safety guard, to protect the wing tips if the airship should pivot on rear landing wheels 3. This device can be folded for easy stowaway in body 1 and opened for attachment to be applied 15 on the wing tips as described.

I have shown a new simplified three-position, single action control system for operating aircraft and roadmobile; also shown is control mechanism to actuate stabilators and slotflectors.

The principal advantages for this control system are that only one movement of the control wheel is possible at one time to actuate controlling means which maneuvers this aircraft along a single flight axis or direction only; also eliminates control feel and coordination of controls as used in conventional aircraft simplifying operation, decreasing flight-learning time and expense.

30 The control wheel is shown in neutral position at 10, Fig. 7, with means for manual movement of wheel to three positions, aft, at 10, dotted, left turning (Fig. 10) and right turning of wheel, eliminating the forward movement from neutral 35 and eliminating the dangerous diving altitudes and preventing this aircraft ever exceeding level flight full power top speeds with resultant increase of aircraft and human safety factors and ease of control in the air and near the ground. 40 Also eliminates foot pedals for control of rudders which is not required for this aircraft.

For maneuvering aircraft, if the wheel 10 and key 13 are moved aft for climbing action, only this single action is possible at one time such as climbing straight after take-off, giving aircraft time to increase speed to a safe margin before turning. Wheel must be returned to neutral position with level flight obtained and resulting increase in forward speed and safety 45 before a turning action is possible if desired, after which it is impossible to climb because key 13 does not mesh with keyway in bracket 14 and hub 15, if aircraft is in a turning maneuver, with aircraft being at a safe high 50 speed non-stall altitude, eliminating danger of stalling on turns.

At certain minimum flight speeds with or without power this aircraft will automatically go into a gliding angle because the stabilators have 55 lower positive pitching moments at slow speeds.

For quick deceleration of aircraft in the air or on landing the stabilator may be controlled to a high drag air brake position and with slotflector also operating to full open position that will also cause drag with resulting deceleration of airspeed quickly and reducing landing area required.

For combined aileron and rudder action for turning this aircraft and for roadable steering, the control wheel is rotated to the left for left turns, as shown, and vice versa.

This operation rotates wheel tube 11 with fore and aft keyway 11a for internal meshing of a 75 key 15a fixed to turning crank 15 which is free

to rotate, but restricted fore and aft by a support bracket.

The control mechanism and operation from the left screw shaft 47 to the left stabilelevator are identical as used for elevator action except the stabilelevator 37 angle being increased to a high stalled negative angle position causing a slight nosing down altitude with decreased air-flow circulation and lift on this left wing panel only with resultant lowering of this wing for banking and combined with the high negative angle of stabilelevator giving a rudder action by causing a high drag coefficient at wing tip, which gives a long moment arm for vertical axis, with resulting rotation around this axis for simultaneously banking and turning of aircraft.

This drag turning action will automatically raise and move the right wing panel forward with the outboard half panel wing leading edge and stabilelevator positioned as such to be deflected at right angles to the relative airflow with resultant increase of lift on this right wing panel for raising and banking this wing to perform a lowered aileron action for turning this aircraft.

The right stabilelevator remains in neutral position to overcome adverse rolling or yawing moments.

Only the stabilelevator controlling actions are required for turning action on this aircraft eliminating slotflectors which must be kept in closed position.

When control wheel is returned to neutral, all control actions as described are reversed and returned to neutral position with resultant level flight altitude.

This machine also has means for converting to a roadmobile for added usefulness and utility by folding the wings as shown, with operating mechanism as shown (Fig. 9).

The basic advantages are detailed simplicity, foolproof operation, reduced weight and cost, overcomes airport inaccessibility and disrupting influence of bad flying weather. Increased utility because machine is complete at all times so that it may be flown whenever the weather is favorable and wherever there is a take-off strip.

Complication of conventional control system is eliminated because only one main control tube 45 is required for controlling this machine simplifying the means of disengaging by having an intermeshing taper key connection 45b having the break line parallel to radius taken from pivoting universal hinge 22 for proper disengagement of taper key. The wing panel control tube 45a will move horizontally outboard in bearings by free operation of stabilelevator allowing taper key on rotating wing panel to clear raising bracket 22F on its swinging operation 22°.

All operations described for roadmobile conversion are reversed, except taper key 45b connection on the control tube 45 that must be meshed by manual operation of stabilelevator for proper connection and operation. If this is not accomplished properly, the operation of screw pin 22g and control tube 45 will be restricted preventing this aircraft from taking off because stabilelevator 37 will not function. This system eliminates accidental disengagement, increases safety and makes the operation of extending wing panels foolproof for safe flight operation.

During flight the safety slot 45c does not mesh with safety lever 22h which is curved to straddle the main control tube 45 to restrict accidental disengagement of connecting pins 22g and 22k 75

and eliminates danger of wing panels folding in flight.

For automobile usefulness, with light weight and low cost, this machine uses a pusher propeller 8 driven directly by engine 5 located at rear upper portion of body 1.

This propelling means 8 is used for flight operation and roadmobile operation eliminating all other means for road propulsion, such as wheel drive or traction by drive shafts, gears, transmission, gear shifting and personal controlling means.

This is the principal reason all present roadables have not succeeded because all had some part of machine removable for roadable use with resulting decrease in utility and were wheel driven with its heavy mechanical and costly complicated devices.

This propelling means giving smoother, high speed vibrationless acceleration on any road surface condition, increases riding comfort and decreases mechanical noises by having a conventional engine muffler for road use and using a conventional slow speed controllable reversible type propeller which is also used for reversing operation on the road.

With the propeller located close to the wing trailing edge, the flight stability and pitching moments are less affected by propeller thrust moments and any danger of the propeller hitting ground at high angle of attack is eliminated.

The wing location at high body position increases the aircraft inherent longitudinal, lateral and directional stability, increases visibility and wing clearance, simplifies the means and ease of rotating and folding the wing panels for roadability and increases the safety factor by the guard action of wing panels and bumper combination around the rotating propeller.

Other advantages for the folded wing panels and propeller combination are increased propulsion efficiency obtained by propeller slipstream flowing aft through the dihedral wing panels forming a Venturi action giving greater forward thrust and acceleration using less engine power and gas consumption.

Other advantages for this machine is the overall simplified construction and efficient form used as shown.

The body 1 is a teardrop form to meet auto standard width to accommodate three persons seated laterally on aircraft center of gravity which eliminates trimming problem and controls.

The body construction consists of a single heavy bulkhead 7 for taking all structural loads imposed on by the addition of fixed parts such as the chassis 7 extending forward for supporting front of body 1 and nose wheel 19 aft is the engine mount tubes 6 which supports the engine 5 and firewall.

Also attached to bulkhead 7 by bearings 2a is a new simplified torsion tube 2 type rear landing gear that takes all landing and roadable shocks by having the wheel axis aft and below torque tube axis so that it will deflect up and aft by vertical and horizontal shocks that twists torque tube freely in fixed support bearings 2a but is restricted further by connecting torque tubes ends 2b together and fixing this to center of bulkhead 7 which absorbs the loads. The landing wheels are conventional tricycle type using a steerable double tire nose wheel 19 which is used for greater landing and roadable stability and safety with rear wheels 3 located behind center of gravity taking all vertical and horizontal

shocks at high stalled take-off and landing altitudes without danger of hitting ground with long body and tail surfaces as with conventional aircraft. This is the principal reason wing leading edge slots are not used on many aircraft.

The wing panel construction consists of a main beam for attaching wing folding fittings and three ribs, the inboard rib, center rib and tip rib which support the outer skins leading edge slat and wing tip.

In Fig. 1 is shown an improved sweepback tapered wing consisting of an inboard half panel having a straight leading edge perpendicular to fore and aft axis to a point halfway along panel after which the outboard half panel leading edge is sweepback to wing tip. The advantages for this wing plan form as shown and in combination with the stabilevators 37 and slotflectors 25 are increased wing lift coefficients by improving spanwise airflow, shifting the aerodynamic center forward with resulting shifting of center of gravity to a more forward and favorable position permitting persons to be located on center of gravity, increasing moment arm, with resulting increase in positive pitching moments for improving take-off and landing efficiency and combined with wind dihedral angle on outboard wing panel which increases the inherent lateral and directional stability and forms the Venturi system when wing panels are folded aft when converted to a roadmobile.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination with a body, of wings at opposite sides of said body, universal joints connecting said body with the inboard ends of said wings at points intermediate the leading and trailing edges of the wings, means on said wings and body for securing said wings to be retained in a horizontal position, means on said body and wings for securing said wings when moved to an inoperative position and substantially parallel to said body, and a ground engaging skid device mounted on and connecting the outer ends of said wings when said wings are in a folded position.

2. In an apparatus of the class described, the combination of a body provided with a rear end, a motor driven propeller on said rear end, and

said body provided at its sides with rearwardly foldable wings, said wings being in vertical position when folded and projecting rearwardly on each side of the propeller converging toward their outer ends, whereby a greater propulsion action is obtained for the apparatus when passing over a highway.

3. In a combined roadmobile and airplane, a body, a pair of monoplane wings, universal joints connecting the inner ends of said wings to the said body, said joints being arranged to permit rotation of said wings between horizontally spread positions and vertically idle positions, said joints being further arranged to permit folding of said wings backwardly in vertical position along said body, means for selectively securing said wings in spread and folded positions, a tie rod detachably connected at its ends to the outboard ends of said wings when folded, and ground engaging guards projecting downwardly from the tie rod to prevent road contact by said outboard wing ends.
